FOOT MASSAGER

Litha M. Tasker, 1314 N. 26th St., Boise, Idaho

Filed Sept. 16, 1964, Ser. No. 31,751

Term of patent 14 years

(Cl. D83—1)

FIG. 1.

FIG. 2.

FIG. 3.

FIG. 4.

FIG. 5.

FIG. 1 is a perspective view of a device for a foot massager, showing my new design.

FIG. 2 is a top plan view thereof.

FIG. 3 is an end elevational view thereof.

FIG. 4 is a longitudinal section on the line 4—4, FIG. 2.

FIG. 5 is a transverse section on the line 5—5, FIG. 2.
I claim:

The ornamental design for a foot massager, substantially as shown.
